UNITED STATES PATENT OFFICE

103,776

DESIGN FOR A BACK GUARD PANEL FOR STOVES

Alexander R. Grant, Chicago, Ill., assignor to
The Moore Corporation, Joliet, Ill., a corpora-
tion of Delaware

Application January 31, 1936, Serial No. 60,931

Term of patent 14 years

To all whom it may concern:

Be it known that I, Alexander R. Grant, a citizen of the United States, residing at Chicago, county of Cook, and State of Illinois, have invented a new, original, and ornamental Design for a Back Guard Panel for Stoves, of which the following is a specification, reference being had to the accompanying drawing, forming a part thereof:

On the drawing,
The single figure is a perspective view of the back guard panel showing my new design.

I claim:
The ornamental design for a back guard panel for stoves as shown.

ALEXANDER R. GRANT.
